UNITED STATES PATENT OFFICE.

ALBERT E. MAYNARD AND WILLIAM A. GUNNING, OF SOUTHBIDGE, MASSACHUSETTS, ASSIGNORS TO AMERICAN OPTICAL COMPANY, OF SOUTHBIDGE, MASSACHUSETTS, A VOLUNTARY ASSOCIATION OF MASSACHUSETTS.

LENS-SURFACING MACHINE.

Application filed April 10, 1919. Serial No. 289,067.

To all whom it may concern:

Be it known that we, ALBERT E. MAYNARD and WILLIAM A. GUNNING, citizens of the United States, residing at Southbridge, in the county of Worcester and State of Massachusetts, have invented certain new and useful Improvements in Lens-Surfacing Machines, of which the following is a specification.

- 10 This invention relates to new and useful improvements in lens grinding machines, and more particularly to a machine for grinding spherical, cylindrical and toric lenses either of the concave or convex type, 15 the primary object of the invention being the provision of a lens grinding machine of this character which is simple in construction and which is thoroughly reliable and efficient in operation.
- 20 Another object of the present invention is the provision of a machine wherein the parts thereof are so arranged as to positively break up the movement between the lens and lap during the grinding operation, 25 whereby the formation of wave surfaces or other imperfections upon the lenses are prevented.

A further object of the present invention is the provision of means whereby the 30 amount of pressure of the lens against the tool may be varied, and to so construct the machines as to permit of a direct pressure of the lens against the tool irrespective of the curve thereon.

35 A still further object of the invention is the provision of efficient means for operating the machine and to provide means for readily and easily placing the lens so as to permit the same to bear directly against the 40 curve of the tool.

With the above and other objects in view the invention consists in the novel features of construction and the combination and arrangement of parts hereinafter more fully set forth in the specification, pointed out in the claims and shown in the accompanying drawings, in which:

Figure I is a side elevation of a grinding machine constructed in accordance with 50 our invention, parts thereof being broken away and illustrated in cross section.

Figure II is a front elevation of my improved grinding machine.

Figure III is a detail top plan view.

Figure IV is a detail rear elevation.

Figure V is a detail plan view illustrating the manner of shifting the power belt.

Figure VI is a perspective view of the machine.

Referring now more particularly to the accompanying drawings, wherein we have illustrated the embodiment of our invention, the numeral 1 indicates the base of the machine which as illustrated is of hollow formation and provided therein with a 65 socket or bearing portion 2, in which is mounted the lower end of the spindle 3. As illustrated, the lower end of the spindle 3 is reduced as at 4 and adapted to fit within a bearing collar 5 to take up the wear within 70 the socket 2. The upper end of the spindle is arranged within a bearing 6 formed in the cover 7, and the extreme upper end of the spindle is reduced as at 8 and fitted within a socket in the lap support 9. The 75 spindle 3 is retained in position within the base by means of the threaded lug 10 removably secured in the lower end of the socket 2.

The supporting member 9 is provided with 80 a stud 11 upon which the lap 12 is mounted, a slot 13 being formed in the lap for engagement with a pin 14 on the stud 11 to prevent rotation of the lap relative to the stud and to provide means whereby other 85 laps may be readily and easily applied to the machine.

Arranged within the base 1 and keyed to the spindle 3 is a gear 15 adapted to mesh with the gear 16 mounted upon the transverse shaft 17 to thus impart a rotating movement to the lap 12 through the spindle. Mounted upon the shaft 17 at one side of the base and arranged exteriorly thereof is a pulley 18 connected by means of the belt 95 19 to the pulley 20 secured to the shaft 21 carried by a swinging carriage. This carriage consists of a transverse bearing portion 22 in which the shaft 21 is mounted and integrally connected with this bearing portion is an arm 23 keyed to a transverse shaft 24 which is mounted in the base 1. The shaft 24 is rotated by means of a hand lever 25 secured to one end of the shaft whereby the actuation of said lever will raise and lower the outer end of the carriage, thus raising and lowering the shaft 21. The lever 25 is held in various adjusted posi-

tions by means of the catch member 26 adapted to engage with the teeth of the rack 27 carried by the base.

In order to impart movement to the various parts of the machine the pulley 28 is secured to the end of the shaft opposite the pulley 18 and is connected to any suitable source of power by means of the belt 29. The pulley 28 is keyed to the shaft 17, 10 and loosely mounted upon the shaft adjacent the pulley 28 is a second pulley 30 whereby the power belt 29 can be readily shifted to this pulley 30 when it is desired to stop the movement of the machine. The 15 belt 29 is shifted from one pulley to the other by means of the spaced arms 31 which are arranged upon opposite sides of the belt and are carried by the bearing 32 secured to the outer end of the longitudinally sliding shaft 33. This shaft 33 is connected at its central portion by means of an arm 34 to one end of a second shaft 35 which extends at right angles to the shaft 33 and having its other end projecting out at the 20 front of the base 1 where a handle member 36 is secured thereto in order to impart movement to the shaft 33 and shift the belt 29 from one pulley to the other.

Rising vertically from the rear portion 30 of the base 1 is a bracket 37 having formed in the front face thereof the channel 38, and having communication with the said channel and extending any suitable distance throughout the width thereof is the slot 39 in which is slidably mounted the supporting stud 40. The stud 40 is provided within its head 41 with a threaded opening 42 through which the screw shaft 43 extends, said shaft having its ends mounted 40 within the side walls of the bracket 37. A suitable guide-way 44 is provided for the head 41 whereby upon rotation of the shaft 43 the stud 40 will be moved laterally within the slot 39. In order to rotate the shaft 43 45 we provide a handle member 45 which is secured to one end thereof upon the outside of one of the walls of the bracket.

The numeral 46 indicates the downwardly projecting bracket portion of the upper 50 or head portion of the machine, which consists of the body portion 47 having extending outwardly therefrom the parallel arms 48 provided with aligned bearing portions 49 disposed at the outer ends of the arms. 55 Extending upwardly and rearwardly from the body portion 47 is a supporting arm 50 provided at its outer end with spaced ears 51. The upper portion of the machine which is indicated generally by the letter 60 A, is mounted for lateral swinging movement upon the pin 40.

To lock the bracket 46 and head associated therewith in desired angularly adjusted position we preferably make use of the bolt 65 52 having a head bearing against the front

of the bracket and extending rearwardly through the slot 57 in the bracket, through an aperture in the plate 56 and through the transverse slot 53 in the member 37. This bolt is provided on its rear with the clamping nut 54 controlled by the handle 55. In use when desired to vary the angle of the machine the nut 54 on the bolt 40 and the screw 43 on the bracket are preferably loosened when the head may be tilted as 70 desired. Should transverse adjustment be desired this may be accomplished thru transverse shifting of the intermediate slide plate 56 and bracket 46 mounted thereon thru the screw 43 engaging the head 41 on 80 the bolt 40, as clearly illustrated in Figures I and IV, this adjustment sliding the entire upper portion laterally with the bolt riding in the slot 53 of the member 37. In this way both transverse and angling adjustments of the head may be readily effected and the parts locked in finally adjusted position by tightening of the respective nuts.

Mounted within the bearings 49 and normally disposed in a substantially vertical 90 position is the upper or lens operating spindle 58, the upper end of which is enclosed within a casing 59. This casing 59 is suitably supported upon the uppermost of the bearings 49 and provided at its upper 95 end with a removable top 60, whereby the spindle 58 may be moved freely within the casing and not moved up through the upper end thereof.

The movement of the spindle is controlled by means of the lever 61, one end of which is pivoted between the spaced ears 51 and the other end provided with a handle member 62. The lever 61 is provided adjacent the handle 62 with a yoke or ring member 94 which encircles the casing 59 and is connected to the upper end of the spindle 58 by means of pins 63 on the thrust collar 100 rotatably held on the stud spindle member 93 as by the washer 101 and lock nut 102, 110 whereby the shifting movement of the lever 61 will raise and lower the spindle 58. In order to retain the spindle in any desired shifted position we mount upon the lever 61 adjacent the handle 62, a sliding block 115 64 provided with finger-pieces 65 whereby the same may be readily actuated. The lever at its outer end is provided with a central bore 66 and mounted therein is a stud 67 formed on the rear face of the catch 68, which is movably mounted within the block 64 and connected therewith by means of the screws 69. The catch as illustrated is provided with a series of teeth adapted for engagement with the teeth of a rack 70 secured to one side of the casing 59.

From the above it will be readily apparent that when it is desired to shift the spindle 58 in either direction the handle 62 is grasped with two fingers engaging the fin-

ger-pieces 65 of the block and as the block is moved toward the handle it will disengage the teeth of the catch from the rack and permit movement of the lever and as soon as the finger-pieces 65 are released the catch will be forced into contact with the rack and securely hold the spindle in its adjusted position. It will be noted that in order to actuate the catch 68, we provide a coil spring 71 which is arranged within the bore 66 and bearing against the stud 67 of the catch 68 whereby to force the teeth of the catch into engagement with the teeth of the rack.

In order to impart a rotary movement to the spindle 58, we mount upon the spindle between the bearings 49 a pulley 72 which is keyed to the spindle whereby to permit the spindle to move therethrough but at the same time impart a rotary movement thereto. Movement is imparted to the pulley 72 through a belt 73 which extends around the pulley 72 and outwardly and downwardly, and thence around the pulley 74 mounted upon the shaft 21. Secured to the rear face of the body 47 of the upper portion of the machine is a bracket 75 having two spaced arms 76 in the outer ends of which a shaft 77 is mounted. Suitable guide pulleys 78 are mounted on this shaft 77 over which the belt 73 passes in order to transfer the position of the belt from a longitudinal to a transverse position and from a transverse position to a longitudinal position. It will be noted that when it is desired to impart movement to the spindle 58 the swinging carriage is lowered by the shifting of the lever 25 in order that the belt 73 may be tightened around the pulley 74. Normally the carriage is in a raised position and the pulley 74 runs loosely within the lower loop of the belt 73. It will be noted that the main purpose of the raising and lowering of the swinging carriage is to apply a pressure upon the belt 73 according to the work which is being done.

In order to maintain the belt 73 in its proper position we provide two guide pulleys 79 which are mounted upon a shaft 80 carried by an angular bracket 81. This bracket 81 is bolted or otherwise secured to the base member 1 by means of the screw bolts 82. It will be noted that the pulleys 79 are arranged upon opposite sides of the inner strand of the belt 73 and guide the same in its movement between the pulley 74 and one of the pulleys 78. From this it will be apparent that the shifting of the upper section A of the machine will not interfere with the operation of the belt 73, as it will be securely held in position by means of the guide pulleys 78 and 79. The lens spindle 58, which is mounted for rotary and reciprocating movement within the bearings 49 of the upper section of the ma-

chine, consists of a tubing member 83 mounted within the casing 84 and is provided at its lower end with a transverse opening 85 in which one end of the crank arm 86 is mounted. The transverse end of the arm 86 which extends through the opening 85 may be adjusted within this opening and is securely held in various adjusted positions by means of the set screw 87. The arm 86 is provided at its lower angular end with an engaging point 88 which engages with the lens block 89, whereby rotary movement of the spindle 83 will thus impart an advancing convolute movement to the lens block 89.

The pulley 72, which is mounted upon the casing 84, is secured to the casing and the spindle 83 whereby these members will rotate together by means of the key 90. This key 90 is provided with inwardly extending portions 91 which engage within suitable longitudinal slots 92 whereby to permit the spindle 83 to be raised and lowered within the casing 84 without interfering with the rotary movement. The upper end of the spindle 83 is connected to the operating lever 61 which raises and lowers the spindle 83 by means of a movable connecting member 93 which is provided with a thrust bearing 103 resting against the shoulder 104 of the stud spindle 93, said bearing including the ring 100 having the laterally extending pins 63 secured to the yoke 94 which encircles the casing 59. The lower end of the connecting member 93 is fitted within the spindle 83 and provided with a transverse pin 95, the ends of which are adapted to fit within the oppositely disposed slots 96 formed within the hollow spindle 83, whereby the lower reduced end of the connecting member 93 will be movable within the spindle 83 to the length of the slots.

When it is desired to lower the spindle so the point 88 will engage with the lens block 89 the finger-pieces 65 are actuated against the tension of the spring 71 to disengage the catch member 68 from the rack 70. The lever 61 can then be moved downwardly with respect to the casing 59, which in turn will force the connecting member 93 downwardly into the spindle member 83 and the pressure against the coil spring 97, which is arranged within the spindle 83, between the end of the connecting member and the lower end of the spindle, will tend to force the spindle downwardly within the casing 84, thus applying pressure to the lens block 89, which is mounted upon the lap 12 for operation. The swinging carriage at the rear of the base is then lowered through the medium of the lever 25, whereby pressure will be applied to the pulley 73 to impart a rotary movement to the spindle 83.

Should it be desired to stop the operation

of the machine without raising or lowering the swinging carriage, the belt shifter can be operated to transfer the power belt 29 from the pulley 31 to the pulley 30, whereby 5 the movement of the machine can be readily stopped without operating the swinging carriage.

From the above description taken in connection with the accompanying drawings, it 10 will be readily apparent that we have provided a simple and durable lens grinding machine wherein the parts thereof are so arranged as to positively break up the movement between the lens and lap during the 15 grinding operation, whereby the formation of wave surfaces or other imperfections upon the lenses will be prevented.

It will be noted from the accompanying drawings that the operation of grinding a 20 lens upon our improved machine is carried out as follows: The lens is first attached to the lens block 89 and then placed in position upon the lap 12. The spindle 83 is then lowered until the point 88 of the arm 86 is 25 engaged with the recess 98 formed in the lens block, and the pressure thereon may be adjusted through the medium of the coil spring 97 disposed within the spindle 83. The belt shifter is then operated to transfer 30 the belt from the pulley 30 to the pulley 31 to thus impart movement to the shaft 17, which in turn is connected with the shaft 21 through the medium of the belt 19 and the pulleys 18 and 20. The swinging carriage 35 is then lowered until sufficient pressure has been applied to the belt 73 so that movement will be conveyed to the spindle 83 through the pulley 72. Should it be desired to apply greater pressure to the grinding of the lens 40 on the block 89 this may be done through the adjustment of the lever 61, and in order to provide more power for this adjustment the swinging carriage is adjusted accordingly by means of the lever 25.

45 Claims:

1. A lens surfacing machine, including 50 a pair of opposed spindles, one carrying a lap, with a lens block thereon, the other of said spindles being adjustable with relation to the former and being of tubular form with a slotted terminal portion at one end, a plunger having a pin engaged in said slotted terminal portion, means for shifting the plunger with, and with 55 respect to the spindle, a spring contained within the spindle and compressible by movement of the plunger with respect to the spindle in one direction, and means for rotating the opposed spindles simultaneously.

60 2. In a machine of the character described, the combination with a head, of an extensible spindle slidable in the head, a spring holding the parts of the spindle in a relatively extended position, a casing enclos-

ing the upper portion of the spindle, and adjusting mechanism shiftable on the casing and including a yoke encircling the casing having portions projecting through the casing into engagement with the spindle for shifting the latter.

3. In a machine of the character described, the combination with a head, of a spindle slidably supported thereby, a casing 75 on the head enclosing the upper portion of the spindle, said casing being formed with longitudinally extending slots, an adjusting means for the spindle having a portion extending inwardly through the slots, the casing being provided with a rack and the adjusting mechanism having a spring latch portion for cooperation with the rack to secure the parts in desired adjusted position.

4. In a lens surfacing machine the combination with a head, of a hollow spindle 80 slidably mounted within the head, means for rotating the spindle, a compressible spring for actuating the spindle in one direction, a controlling device therefor including a plunger member having projecting pins, the spindle having slots to receive the pins connecting the plunger and spindle for limited sliding movement, one 85 end of the actuating spring contacting with the plunger and the other with the spindle, and means for securing the plunger in desired adjusted position to vary at will the position of the spindle or the compression of the spring.

5. A machine of the character described including a head, a hollow spindle journaled in the head having intermediately slotted walls, an actuating spring mounted within the hollow spindle, a plunger member fitting 90 within the spindle and having pins sliding in the slots of the spindle for connecting the parts, a pivoted lever connected with the plunger, and means for locking the lever in desired adjusted position to control the 95 position of the plunger and parts associated therewith.

6. In combination with a base and lap 100 of a lens surfacing machine, a fixed support mounted on the base, a movable head carried by the support, spaced arms carried by the head, a movable two part hollow spindle carried by said arms, a crank arm carried by the lower part of the spindle, an actuating 105 spring mounted within the spindle and being under compression between the two parts of the spindle, and means for raising and lowering the spindle, said means placing the crank arm under spring pressure when in a lowered position.

7. A grinding machine including a base 110 having a rotatable lap, with a lens block or holder thereon, a fixed support, a movable support carried by the fixed support and adapted for swinging angular adjustment, a 115

tubular telescopic spindle carried by the movable support, a crank arm at one end of the spindle, a coil spring arranged within the spindle and between the telescopic members of the spindle, means for adjusting the spindle longitudinally whereby to lower the spindle and at the same time retain the crank arm under compression through the medium of the spring when in its lowered position, and means for retaining the longitudinally adjustable spindle in a raised or lowered position.

8. A lens surfacing machine including a head, a spindle slidably and rotatably mounted within the head, a plunger member associated with the spindle for relative sliding movement with respect thereto, an actuating spring for the spindle adapted to be compressed by sliding movement of the plunger, a lever pivoted to the head and having connection with the plunger, a rack carried by the head, and a latch member on the lever for adjustable engagement with the rack to lock the lever in desired position and secure the plunger in place.

9. A surfacing machine of the class described, including a base, a rotating lap mounted thereon, and including a lens block or holder, a bracket carried by the base, a movable member carried by the bracket, a hollow spindle opposed to the lap and carried by the movable member and provided with a crank arm at its lower end, a spring within the spindle, a second movable member having a sliding connection with the spindle, a compression spring disposed between said second movable member and the spindle, a lever pivotally mounted upon the first movable member and connected with the second movable member and adapted for manual adjustment, whereby to raise and lower the spindle, and means for retaining the lever in a raised or lowered position.

10. In a machine of the character described, the combination with a head, of a spindle slidably mounted in the head, a casing enclosing the spindle, said casing having longitudinally extending slots formed therein, a lever pivoted to the head and provided with a shift yoke embracing the casing, connections between the shift yoke and spindle by way of the slots, and a resilient locking device carried by the yoke for engagement with the casing to secure the yoke and associated parts in desired relatively adjusted position.

11. In a machine of the character described, the combination with a head, of a spindle slidably mounted in the head, a casing enclosing the spindle, said casing having longitudinally extending slots formed therein, a lever pivoted to the head and provided with a shift yoke embracing the casing, connections between the shift yoke and

spindle by way of the slots, and a resilient locking device carried by the yoke for engagement with the casing to secure the yoke and associated parts in desired relatively adjusted position, the casing having a rack portion for engagement by said resilient locking device.

12. A machine of the character described including opposed rotatable spindles and means for driving the spindles, including a driving shaft operatively associated with one of the spindles, a driven shaft, a belt connection between the driving and driven shafts, and a second belt connection between the driven shaft and the other spindle, and a rock arm support for the driven shaft pivoted intermediate and slightly off the center line between the driven and driving shafts whereby rocking of the arm will slightly increase the distance between the driving and driven shaft to slightly increase the tension on that connecting belt for a given amount of movement while considerably increasing the tension on the belt to the spindle, and means for securing the rock arm in various adjusted positions.

13. A lens surfacing machine, including a rotatable spindle, with a lap and lens block or holder associated therewith, a second sectional spindle opposed thereto and carrying a crank arm, said second spindle including a concentric sleeve portion, an actuating spring contained within the sleeve portion, and a plunger member slidable within the sleeve portion and engaging the spring, expansion of the spring actuating the crank arm against the first mentioned spindle and in line with the axis of the second spindle.

14. A lens surfacing machine including a main supporting frame and a pair of opposed spindles contained within the frame, a rotating lap and a lens block or holder associated with one of said spindles, the other spindle being angularly adjustable as respects the other and formed of concentric extensible sections, a spring disposed between the concentric sections and normally tending to separate the same, a crank arm carried by one of the sections and adapted to be pressed against the opposed spindle by the spring, a pivoted yoke attached to the other section for moving the spindle longitudinally of its axis, and a spring-pressed latch carried by the yoke to lock same in adjusted position.

15. In combination with the main frame and lap of a lens surfacing machine, a spindle housing supported by the frame, a tubular spindle mounted in the housing and having a crank arm opposed to the lap, a plunger slidable in the housing and having a reduced portion extending into the tubular spindle, a compression spring within the spindle and acting against the plun-

ger, a pivoted yoke surrounding the housing and carrying the plunger, whereby to adjust the spindle longitudinally, and a spring-pressed locking means carried by the yoke and adapted to engage serrations on the exterior of the housing.

16. In a lens surfacing machine, the combination with a pair of opposed spindles, of means for rotating the spindles simultaneously, one of the spindles carrying a lap with a lens block thereon, the other consisting of telescopic sections, a plunger mounted in and having a sliding connection with one of the sections, the sliding connec-

tion preventing rotation of the plunger, a spring contained within the spindle and compressible by movement of the plunger in one direction with respect to the spindle, and means for shifting the plunger with respect to the spindle. 15

20 In testimony whereof we have affixed our signatures, in presence of two witnesses.

ALBERT E. MAYNARD.
WILLIAM A. GUNNING.
